Charles H. North,

By his Attorney,

Thurston & Bates

UNITED STATES PATENT OFFICE.

CHARLES H. NORTH, OF CLEVELAND, OHIO, ASSIGNOR TO THE NORTH ELECTRIC COMPANY, OF SAME PLACE.

TELEPHONE-RECEIVER.

SPECIFICATION forming part of Letters Patent No. 670,564, dated March 26, 1901.

Application filed September 27, 1899. Serial No. 731,798. (No model.)

To all whom it may concern:

- Be it known that I, CHARLES H. NORTH, a citizen of the United States, residing at Cleveland, in the county of Cuyahoga and State of Ohio, have invented a certain new and useful Improvement in Telephone - Receivers, of which the following is a full, clear, and exact description, reference being had to the accompanying drawings.
- 10 The object of my invention is to provide a telephone - receiver, which while being simple and cheap in construction, shall, first, minimize the disadvantages resulting from the different rates of expansion of the material comprising the receiver; second, shall be conveniently adjustable to regulate the distance between the magnet - poles and the diaphragm, and, third, shall have no exposed binding-posts.
- 20 The invention consists in the means I employ for attaining these ends or material parts thereof, as hereinafter specified, and definitely set out in the claims.

- The drawings clearly disclose my invention.
- 25 Figure 1 is a vertical central section of the receiver complete. Fig. 2 is a side elevation of the interior of the receiver, and Fig. 3 is a vertical central section at right angles to Fig. 2. Fig. 4 is a perspective view of the electromagnets and the brass block which holds them in place. Figs. 5 and 6 are horizontal sections, respectively, on the lines 5 5 and 6 6 of Fig. 2. Fig. 7 is a top view of the interior 35 of the receiver, the diaphragm being partly broken away.

- Referring to the parts by letters, A represents the body of the casing, preferably made of hard rubber, and B the cap therefor, which 40 screws onto the outside of the body by the internal threads b.

- C represents a frame which is preferably a brass cup or cone-frustum having a flange c taking over the upper end of the body A. 45 This flange has external threads c', which mesh with the threads b on the cap B. Extending across the mouth of the cup, between it and the cap, is the diaphragm D.

- The permanent magnet is preferably a single horseshoe-magnet, or, if desired, two in-

dependent bar-magnets secured together may be employed. The two legs or bars of the magnet are indicated by E. Near their upper ends they are cut back, as at e, sufficiently to receive the cores F, which carry the 55 electric winding f. Between the two bars E is the brass block G. This block is in the form of a mutilated cylinder having two opposite sides which are screw-threaded, as at g, but between them being recessed, as at g'. 60 The recessed part lies between the bars E E, while the screw-threaded part projects over beyond the edges thereof. A screw-bolt H clamps the block, the electromagnets, and the permanent magnet all together by screwing through one bar E and through the intermediate parts into the other bar. The cup C screws onto the block G by reason of the threads g thereon and internal threads on a flange c², depending from the cup. A pair of 65 jam-nuts J and J' also screw onto the block G and lock each other and the cup C. This method of supporting the magnet reduces to a minimum the disarrangement of the parts by unequal expansion or contraction. The 70 difference in expansion between the cores F and the cup C (these being the parts which are factors in the result) is insignificant, while if the magnet were supported at its lower end by the rubber casing, as has been 75 customary, the different rates of expansion between the steel and rubber are sufficient to be very annoying.

The receiver is easily adjusted to the point of greatest efficiency. The casing A is unscrewed from the cap B, and the jam-nuts J and J' loosened, and the cup C turned in one direction or the other, as required, (thus moving the diaphragm toward or from the magnet-poles,) and is then locked by the jam-nuts. 80 85 90

Since the cup C is screw-threaded to the cap, the removal of the casing A does not in the least interfere with the electric operation of the receiver, and the latter may thus be adjusted by sound, which is much more accurate than by measurement.

By making the external diameter of the cup C the same as that of the head of the casing A the thread b on the cap is made continuous, which is not only the simplest and cheap- 95 100

est form, but allows the casing A to abut against the flange c' of the cup, and thus act as a jam-nut for it.

The ends of the coil f of the electromagnets 5 are secured to insulated wires K, which pass down through a pair of longitudinal holes g² in the block G. At their lower ends these wires are secured by screws L (which take into an insulating-block M, held between the 10 bars E) to the two ends of the flexible cord N. In order to prevent a sudden shock on the cord from pulling it loose from the screws or from dislocating the latter, the two ends of the cord cross over from one side of the 15 block onto the other through the opening m therein. The two ends come together beneath the magnet and pass out of the casing through the opening a as one cord.

By making the connection with the flexible 20 cord entirely within the casing a very neat appearance is given to the receiver, and, moreover, the possibility of a shock from an accidental contact with exposed binding-posts or the accidental disconnection of the cord 25 therefrom is obviated.

I claim—

1. In a telephone-receiver, in combination, 30 a casing-body, a cap secured to the same, a cup within the casing having a projection extending between the cap and body, a diaphragm between the cup and cap, and a magnet carried by said cup and adjustable with reference thereto, substantially as described.

2. In a telephone-receiver, a horseshoe- 35 magnet, a cup supporting said magnet, and adjustable along it by reason of screw-threads, a diaphragm extending over the mouth of the cup, said cup having a peripheral flange, combined with a casing consisting of a body and 40 a cap screwing thereonto, said peripheral flange extending between said cap and body and being clamped thereby, substantially as described.

3. In a telephone-receiver, a casing consisting of a body and a cap adapted to be secured 45 directly thereto, a cup within the casing screwing into the cap, whereby said cup is held by the casing and entirely inclosed within it, combined with a diaphragm between the cup and cap, and a magnet carried 50 by the cup, substantially as described.

4. In a telephone-receiver, a casing consisting of a body and a cap screwing directly 55 thereonto by reason of internal threads on the cap and external threads on the body, a cup within the casing having a flange extending between the cap and body and having screw-threads on its exterior, said screw-threads being adapted to form a continuation 60 of the screw-threads on the body whereby the same internal threading on the cap may mesh with both the cup and body, combined with a diaphragm between the cup and cap, and a magnet carried by the cup, substantially as 65 described.

5. In a telephone-receiver, in combination, 70 a cup having a flange screw-threaded on its

exterior and an opening through it screw-threaded on its interior, a horseshoe-magnet carrying a screw-threaded block engaging 75 with said interior screw-threads whereby the cup adjustably supports the magnet, a cap screwing onto said cup, a diaphragm between said cap and cup, and a casing-body having external screw-threads and screwing directly 80 into said cap, whereby said cup is entirely inclosed within the cap and body and clamped thereby, substantially as described.

6. In a telephone-receiver, a pair of magnet-bars E, an insulating-block M between 85 the same, said block having an opening m, a double flexible cord dividing and passing onto opposite sides of said block and passing through the opening m in opposite directions, electromagnets carried by said bars E, and 90 conductors leading therefrom to opposite sides of said block and there secured to the flexible cord, in combination with a diaphragm which said magnets are adapted to operate, and an insulating-casing inclosing 95 the parts and having an opening through which the flexible cord extends, substantially as described.

7. In a telephone-receiver, the combination 100 with a frame, a diaphragm in contact therewith, and a magnet carried by said frame, of a cap detachably secured to said frame and a shell detachably secured to said cap, the cap and shell inclosing the other parts, substantially as described.

8. In a telephone-receiver, the combination 105 with a frame, a magnet adjustably mounted in said frame, and a diaphragm, of a cap detachably secured to said frame and arranged to hold the diaphragm to the frame, and a shell detachably secured to the cap, substantially as described.

9. In a telephone-receiver, the combination 110 with a frame, a magnet provided with a head screw-threaded into the frame, and a diaphragm in contact with said frame, of a cap screw-threaded onto said frame and inclosing the diaphragm, and a shell screw-threaded onto the cap and inclosing the magnet, substantially as described.

10. In a telephone-receiver, the combination 115 with a hollow cone-frustum frame having an interior screw-threaded portion at its smaller end and an exterior threaded portion at the larger end, of a diaphragm in contact 120 with the end surface of the large end of the frame, a magnet provided with a magnet-head having a screw-thread engaging the interior screw-threads in the magnet-frame, a cap provided with screw-threads engaging the 125 exterior screw-threads of the frame, and a shell inclosing the magnet and provided with screw-threads engaging the cap, substantially as described.

11. In a telephone-receiver, the combination 130 with a frame, a magnet having a head screwed partly into said frame, and a lock-nut on said head and arranged to engage the frame, of a diaphragm, a cap detachably se-

cured to the frame and inclosing the dia-
phragm, and a shell detachably secured to
the cap and inclosing the magnet and lock-
nut, substantially as described.

- 5 12. In a telephone-receiver, the combina-
tion, with a pair of magnet-legs, a diaphragm,
coils, and means for holding said magnet-
legs, coils and diaphragm in proper relation
to each other, of a filling-piece between the
10 legs of the magnet and provided with a trans-
verse opening, a pair of conductor-cords in
electrical communication with the respective
terminals of the coils, said conductor-cords
being interlaced through the opening in the
15 filling-piece, and a shell arranged to inclose
the magnet, coils and filling-piece and pro-
vided with an opening through which the
conductor-cords pass to the outside, substan-
tially as described.
- 20 13. In a telephone-receiver, the combina-
tion with a magnet, coils and diaphragm, and
means for holding them in their proper rela-

tion to each other, of binding-posts mounted
in fixed relation to the coils and connected
to the terminals thereof, a pair of conductor-
cords, means for making an electrical con-
nection between the electrical conductors of
the conductor-cords and the said binding-
posts, means for securing the conductor-cords
25 to the receiver, and a shell inclosing the mag-
net, coils, binding-posts and securing means
and provided with an opening through which
the conductor-cords extend, whereby the re-
ceiver may be suspended from said cords with-
out straining the electrical conductors within
30 the conductor-cords or the binding-posts, sub-
stantially as described.

In testimony whereof I hereunto affix my
signature in the presence of two witnesses.

CHARLES H. NORTH.
